UNITED STATES PATENT OFFICE.

ALBERT E. HURST, OF NEW YORK, N. Y., ASSIGNOR TO TEXTILE PUBLISHING COMPANY, OF NEW YORK, N. Y., A CORPORATION OF NEW YORK.

PICTORIAL ILLUSTRATION.

Application filed March 29, 1927. Serial No. 179,312.

This invention relates to the production of a pictorial illustration which is particularly intended for advertising purposes. It has for its object to provide such an article 5 which is made up in a semi-finished form. In such form it is sold to stores, business houses or the like, who can have their own artist complete the unfinished parts of the drawing so that it displays their own particular merchandise.

A further object of this invention is to provide an illustration for advertising purposes which will greatly save the time and expense of a merchant in producing cuts for 15 advertising matter or the like and which will enable the resultant cuts produced to very originally, effectively and accurately show the specific merchandise which is being advertised.

With these objects and such other objects as may hereinafter appear, in view, I have devised the particular arrangement shown and described herein and more specifically 20 pointed out in the claims appended hereto.

Reference is to be had to the accompanying drawing, in which

Figure 1 is a view showing a drawing in the incomplete form in which it is produced by one artist and in the form in which 30 it is sold by an advertising concern or the like to a store.

Figure 2 is a view of the drawing shown in Figure 1 except that said drawing has been completed by the addition of a garment, this addition being made by an artist 35 secured by the store or other concern to whom the original drawing semi-finished as shown in Figure 1 was supplied.

Throughout the various views of the 40 drawings, similar reference characters designate similar parts.

My improved drawing or pictorial illustration may be adapted for use in the display or advertising of any kind of merchandise. It is particularly adapted for use in advertising of articles of clothing, such as ladies' or men's garments, and I have therefore illustrated a drawing as is applicable for such articles.

50 In Figure 1 is shown the drawing in semi-completed form such as is furnished by an advertising concern to a store or the like which wishes to advertise its merchandise pictorially.

55 The drawing disclosed in Figure 1 is

made up of finished and unfinished parts. For instance, it will be seen that the head 1 is completely finished in all of its details, and it is drawn or printed in full lines in black ink, or any ink of such a color as 60 will reproduce perfectly by normal photography. It will also be seen that the hands 2 and the legs and feet 3 are also similarly shown in detailed completed form and are reproduced in similar ink. Such articles as 65 the fur piece 4 and necklace 5 are also shown in detailed completed form in the black ink or the like.

The body of the figure shown is merely outlined in more or less general form, as is 70 disclosed in dotted lines at 6. The ink used in printing this outline 6 is of a blue color or it may be of any other color that will not reproduce by normal photography.

The drawing therefore, in the form shown 75 in Figure 1, is made up of detailed completed parts and of outlined or uncompleted parts. Such completed parts comprise the head 1, hands 2, legs and feet 3, fur piece 4 and necklace 5. The uncompleted or outlined parts of this drawing comprise the outline of the body 6, including the outline of the arms, these uncompleted parts being printed or drawn in as was heretofore explained, in a blue colored ink or any colored ink which is not reproductive by photographic process.

The drawing shown in Figure 1 is printed 80 in quantities and may be sold or otherwise supplied to stores or other business houses for completion by them. The completion of this drawing can be had by any artist connected with the store or otherwise obtained. Such artist merely proceeds to draw upon 85 the figure a dress, coat, suit or such other garment as may be required to be advertised. This is a very simple procedure and does not require the services of a highly skilled artist since the more difficult parts to draw, such as the head, face, hands, legs and feet, 90 as well as the general posture of the figure, have already been made by a highly skilled fashion artist and are supplied as part of the original drawing shown in Figure 1.

In Figure 2 is shown the completed drawing. The same is composed of the previously 100 supplied finished parts 1, 2, 3, 4 and 5, and in addition, a dress 7 has been drawn on the figure. It will be seen that in drawing such dress or other garment 7 on the figure, the 110

blue outline 6 may be departed from to such an extent as may be necessary to properly draw the garment. Said blue outline 6 is merely originally provided for the purpose 5 of giving a general idea of the form and posture of the figure. Naturally, slight variances therefrom will be had when drawing different types of garments on the figure. The fact that the blue outline 6 will appear upon the finished drawing, such as is indicated in Figure 2, will not in any way complicate the making of an electrotype or cut from the finished drawing. The outline 10 6 being formed of blue ink does not reproduce when photographed and the finished drawing, merely composed of the parts 1, 2, 15 3, 4, 5 and 7 will be reproduced when the sketch shown in Figure 2 is photographed.

From the foregoing, it will be apparent 20 that a drawing such as shown in Figure 1 is of considerable value for advertising purposes. A drawing as shown in said figure may be originally made by a highly skilled artist and it includes in finished form, such 25 parts of the drawing as are usually found difficult to draw. It also discloses the general posture of the figure, so that when a printed reproduction of this drawing is purchased by a storekeeper or the like, all he 30 has to do is secure the services of any available artist to sketch on the printed figure, any garment which he desires advertised. The same figure can readily be adapted for 35 a waist, coat, suit or dress. The resultant drawing, an example of which is shown in Figure 2, may then be photographed for the purpose of producing a cut or electrotype and the blue outline 6 will be invisible in the resultant photograph from which the 40 cut or electrotype is made.

The furnishing of printed reproductions of such drawings as shown in Figure 1 is particularly of great aid to storekeepers or business houses in small towns or cities and 45 who would like to use original drawings or cuts in displaying their merchandise, but have been unable to do so by reason of the inaccessibility of talented fashion artists. When a reproduction of a drawing such as

is shown in Figure 1 is provided, a person 50 of but little artistic skill can readily sketch in on the view shown in Figure 1, a garment such as is desired to be advertised by the merchant.

While I have described my invention as 55 being applied to drawings intended to be used for the display or sale of wearing apparel, it is apparent that the same may be readily used for the display of any kind of merchandise as the principle involved is the 60 same in each case.

Having described my invention, what I claim is:

1. An article of the class described, comprising a pictorial illustration consisting of 65 a figure having finished elements drawn or printed in ink of a color capable of photographic reproduction, and having other parts in unfinished form, drawn or printed in an ink of a color not reproductive by normal photography, said unfinished parts acting as a guide for the drawing of additional finished parts, which are adapted to co-operate with the initially finished parts to complete the figure. 75

2. An article of the class described comprising an illustration showing a figure, parts of said figure being produced in detail and printed in an ink capable of photographic reproduction, other parts of said figure consisting mainly of outline and being printed in ink incapable of reproduction by normal photography, said outlined parts being adapted to act as a guide for the making of finished parts to complete the picture. 80 85

3. The process of making an illustration consisting in printing parts of the illustration of an object in an ink capable of photographic reproduction, and in printing other parts in an ink of non-actinic value and thus 90 incapable of photographic reproduction, and in utilizing the lines printed in non-actinic ink as a guide for drawing in finished parts which co-operate with the initially finished parts to complete the picture. 95

Signed at the city, county and State of New York, this 28th day of March, 1927.

ALBERT E. HURST.
